UNITED STATES PATENT OFFICE.

CHARLES FREDERICK CRAIG, OF SAN FRANCISCO, CALIFORNIA, ASSIGNOR TO CRAIG GOLFEMETER CO., OF WILMINGTON, DELAWARE, A CORPORATION OF DELAWARE.

CAPTIVE PLAYING BALL.

Application filed September 3, 1921. Serial No. 498,215.

To all whom it may concern:

Be it known that I, CHARLES FREDERICK CRAIG, a citizen of the United States, residing at the city and county of San Francisco and State of California, have invented certain new and useful Improvements in Captive Playing Balls, of which the following is a specification.

My invention relates to playing-balls held captive by a line which defines their path, and limits their projection, under the force of a delivered blow. Such balls, though they may be of varied nature and used in a variety of games, are most commonly golf-balls, and are used in connection with an anchor device to which they are held captive, and which registers and indicates the character, force and effect of the blow, thereby affording convenient and satisfactory golf-practice, in so far as improvement in stroke is the end desired.

In practice of this nature, the blows delivered, being, principally, "drives," are particularly forceful; and it is, therefore, a matter of prime importance to provide a secure and durable connection between the captive line and ball. Approved practice, in this regard, comprises some form of attachment through the diameter of the ball, and a pliable, metallic cable, tough under flexure, and of great tensile strength. Experience has shown, however, that the cable under the repeated, sudden and violent bending strain imposed upon it in the immediate vicinity of the ball, often breaks at that point, so that the freed ball becomes an element of danger and destruction. Although it may not be possible to absolutely insure the cable against breaking, it is possible to reinforce it at this point, and thus reduce its liability to rupture; but, further than this, it is possible, in connection with this reinforcement, to make it serve the desirable purposes of temporarily still holding the ball captive, even though the cable should break, and of giving warning of the rupture in order that the ball may be discarded before it may, by continued use, finally break all connection and become free.

These are the objects of my invention, and to this end my invention consists in the novel captive playing-ball which I shall now fully

describe, by reference to the accompanying drawings, in which—

Fig. 1 is a side elevation of my captive playing-ball, the captive line being broken.

Fig. 2 is a diametrical section of the same, enlarged, and broken, the dotted lines showing the region of greatest flexing stress on the captive line.

Fig. 3 is a longitudinal section enlarged of the outer end of the captive line and the reinforcing member.

Fig. 4 is an end view of the same.

1 is a ball, here indicated, for illustration merely, as a golf-ball. Through the ball diametrically is made a hole in which is fitted a wearing lining, preferably in the form of a metallic tube or thimble 2, the ends of the tube being swaged and flanged outwardly and down upon the ball surface, as shown at 2'.

3 is the captive line. In its best form this line is a flexible metallic cable of suitable nature. The cable passes freely through the metallic thimble 2; and upon its extremity is fitted a funnel-like collar 4 larger in diameter of base than the diameter of the bore of the thimble, whereby said collar is adapted to fit nicely and approximately flush in the outer end of the thimble while holding the ball on the cable. The strands at the cable extremity are separated and soldered down into the concavity of the collar as indicated at 4'.

Fitted around the cable helically, is a flexible reinforcing member 5, preferably metallic, having the general shape and appearance of a closely coiled spring. The outer end of this member 5 is made fast to the end of the cable, as, for example, by means of solder applied near the collar 4, as shown at 5'. Said member thence passes freely through the thimble 2 of the ball, and extends along the cable a distance beyond the inner side of the ball sufficient to cover and protect that portion or section of the cable in the vicinity of the ball which is, as above stated, and as indicated by the dotted lines in Fig. 2, peculiarly susceptible to the flexing stress of the delivered blow, and at its inner end said member is made fast to the cable, as by soldering, as indicated at 5''. In practice this distance is about an inch and a half

more or less, but may be varied if desired, the only requirement being that said member extends far enough beyond the ball to resist the bending strain which is greatest 5 in the vicinity of said ball.

The ball is freely slideable and rotatable upon the helically reinforced cable passing through it, the thimble in said ball taking care of the wear.

10 It will now be seen that the member 5 not only reinforces and strengthens the cable in the section most needing such provision, but also, has the effect of still holding the ball captive, even though, as sometimes happens, 15 the cable breaks within the inclosure of said member, because said member is made fast at its inner end to the cable; and it also has the further purpose and effect of giving information of said break, and thus giving 20 the user timely warning to desist from the use of the ball, this fact being manifest by the undue spreading of the coils of the helical member 5, in the neighborhood of the break, due to the distortion of the broken 25 cable within it.

I have not deemed it necessary to show or describe any anchor device for the other end of the cable, it being understood that the cable is suitably connected with any suitable appliance to fulfil the purpose and use 30 of the captive ball.

I claim:

1. A captive playing-ball comprising a ball; a cable passing through and headed 35 beyond said ball; and a helically wound,

flexible, reinforcing member fitted upon the cable and extending from the headed end thereof, through and beyond the ball and made fast at its inner end to said cable.

2. A captive playing-ball comprising a 40 ball; a cable passing through and headed beyond said ball; and a helically wound, flexible, reinforcing member fitted upon the cable and made fast to its headed end, said member thence passing through and beyond 45 the ball and made fast at its inner end to said cable.

3. A captive playing-ball comprising a ball; a wearing thimble passing diametrically through and secured to said ball; a 50 cable passing freely through and headed beyond said thimble; and a helically wound, flexible, reinforcing member fitted upon the cable and extending from the headed end thereof freely through and beyond the thimble, and made fast at its inner end to said cable. 55

4. A captive playing-ball comprising a ball; a wearing thimble passing diametrically through and secured to said ball; a 60 cable passing freely through and headed beyond said thimble; and a helically wound, flexible, reinforcing member fitted upon the cable and made fast to its headed end, said member thence passing freely through and 65 beyond said thimble and made fast at its inner end to said cable.

In testimony whereof I have signed my name to this specification.

CHARLES FREDERICK CRAIG.
